UNITED STATES PATENT OFFICE

2,456,340

VENTILATOR

Harold F. Tideman, Kenilworth, Ill.

Application June 30, 1945, Serial No. 602,594

3 Claims. (Cl. 98—94)

1

The present invention relates to ventilating fans and is particularly directed to the provision of a device of this character wherein the fan may be disposed in a window or other opening in such a way that when the fan is in use it lies in the proper position to direct air through the opening and when the fan is not in use, it is moved into an inoperative position and carries with it a closure for the opening.

My invention contemplates the provision of a supporting device consisting of what I may call two plate sections angularly disposed with respect to each other and meeting substantially on a hinge line where a hinge is provided to mount the device in such opening. Either plate section may be locked to the casing of the opening and the other plate section will thereupon stand out from the opening toward the outside or the inside as the case may be. The preferred angle between the plate sections is such as to prevent substantial interference with the air stream from the fan. The fan is mounted in one plate section and may comprise a simple framework that is mounted by a hinge at the opening. The other plate section may be either transparent or opaque, and may be cut down to fit different sizes of openings.

The nature and advantages of my invention will appear more fully from the following description and the accompanying drawing wherein a preferred form of the invention is shown. It should be understood however that the drawing and description are illustrative only and should not be taken as limiting the invention except insofar as it is limited by the claims.

In the drawing:

Figure 1 is a vertical sectional view through a window to which my device has been applied;

Figure 2 is a perspective view of a completed unit which is adapted to be inserted in the place of a section of the glass in the window;

Figure 3 is a view similar to Figure 2 but with the parts in their alternative position; and

Figure 4 is an enlarged sectional view taken vertically through the device substantially on line —4 of Figure 2.

Referring now in detail to the drawings, the present invention is adapted to be applied to an opening, such as a window 5, the upper section of which is provided with several panes of glass, such as that shown at 7 in Figure 1. The lower section 8 of the window may have one or more panes of glass. This particular type of window is selected because of the ease with which my invention may be applied thereto. However,

2

it is obvious the invention is not limited to any particular type of window or opening, the device itself being complete and adapted to be mounted in any opening.

The device comprises a main frame 9 which may be of any desirable width and which may be constructed of any suitable material, preferably a transparent sheet material, that can be cut down to fit any particular opening. Figures 10 and 4 show dotted portions 9a and 9b that can be cut off to bring the frame 9 down to the size shown in full lines. An example of a suitable material is the transparent resin product sold under the trade name of "Lucite." The frame 9 has a hinge 10 along its upper inner edge, this hinge preferably being of the continuous or piano type. The hinge supports two plate sections 11 and 12 which are angularly disposed with respect to each other and which may be integral or fixed to each other in any suitable fashion so as to stand at a desired angle with respect to each other. I find that the most desirable angle for my purpose is one in the neighborhood of 60 degrees, as this allows the fan to operate at a relatively high efficiency without making it necessary for the fan to stick out into the room against drapes or shades to an objectionable degree. The frame 9 preferably carries a latch pin 13 which is adapted to engage both sides of the edge of either section 11 or 12 to lock the same in fixed position.

A fan 14 is mounted by means of a spider framework 15 in an aperture 16 provided in the plate section 11. In addition to the spider I also provide the fan with a guard 17 consisting of a number of bars or wires curved as shown in front of the blades of the fan 14. The fan is driven by a motor 18 which is supported in the spider 15 and which may be energized in the usual manner by connecting a cord leading therefrom to a current outlet within the room.

It is believed that the operations of the device will be readily understood. If it is desired to have the fan in operation to drive air from a room, the parts are arranged as shown in Figure 2 and the fan is energized. If the fan is to drive air into the room, then the fan parts would be reversed on the plate section 11. Whenever it is desired to have the window closed the fan is stopped, the catch 13 is released and the parts are swung into the position shown in Figure 3. In this position the plate section 12 closes the opening in the frame 9 leaving the parts to serve merely as a closure for a certain section of the window or opening. It is evident that if the sec-

tion 12 be made of a transparent material, there will be little obstruction to light by the use of this device. In fact, the plate section 11 may also be of a transparent material that will admit light. The frame 9 preferably is made of a material that is easily cut to size thus making it unnecessary to have different sizes of fan units for different sizes of openings.

Having thus described my invention, I claim:

1. A ventilating fan adapted to replace a window pane in a window comprising a supporting framework having an aperture therein, a fan carrying framework movable into and out of the aperture in said frame, and a closure for the aperture in said frame fixed to the fan carrying framework to move therewith, said closure and fan carrying framework being so positioned with respect to each other that when one is in the aperture in the frame the other one projects laterally from the frame.

2. A ventilating unit comprising a mounting frame adapted to be inserted in an opening, a pair of plate sections angularly disposed with respect to each other, and joined at their upper edges, hinge means at the junction of said plate sections for mounting them in said frame, and

5 a fan unit carried by one of said plate sections.

3. A ventilating fan adapted to replace a window pane in a window comprising a supporting framework having an aperture therein, a fan carrying framework movable into and out of the aperture in said frame, and a transparent closure for the aperture in said frame fixed to the fan carrying framework to move therewith, said closure and fan carrying framework being so positioned with respect to each other that when one is in the aperture in the frame the other one projects laterally from the frame.
